INVENTOR

John S. Fielder,
BY Drake & Co. ATTY'S.

UNITED STATES PATENT OFFICE.

JOHN S. FIELDER, OF ASBURY PARK, ASSIGNOR TO HIMSELF, THOMAS E. WARMAN, OF OCEAN BEACH, GEÓ. A. WEDEL, OF ASBURY PARK, AND JOSIAH T. MARTIN, OF NEWARK, NEW JERSEY.

PAPER-BAG FASTENING.

SPECIFICATION forming part of Letters Patent No. 424,411, dated March 25, 1890.

Application filed April 27, 1889. Serial No. 308,832. (No model.)

To all whom it may concern:

Be it known that I, JOHN S. FIELDER, a citizen of the United States, residing at Asbury Park, in the county of Monmouth and State 5 of New Jersey, have invented certain new and useful Improvements in Bags; and I do hereby declare the following to be a full, clear, and exact description of the invention, such as will enable others skilled in the art to which 10 it appertains to make and use the same, reference being had to the accompanying drawings, and to letters of reference marked thereon, which form a part of this specification.

The object of this invention is to simplify 15 the securing of the contents of a bag and dispense with cords and strings as ordinarily used.

The invention consists in permanently securing to a bag an elastic band or loop and the combinations thereof, substantially as will 20 be hereinafter set forth, and finally embodied in the claims.

Referring to the accompanying drawings, in which like letters of reference indicate corresponding parts in each of the several figures, Figure 1 is a perspective view of a bag 25 with my improvement. Fig. 2 is a plan view of the stiffening or strengthening piece; and Fig. 3 is a section through line *x* in Fig. 1, showing only the band, stiffening-piece, and 30 cross-bar.

In said drawings, *a* represents an ordinary paper bag with a bottom-inclosing flap *b*. Upon the side of the bag near the bottom is a stiffening and strengthening piece *c*, with 35 an opening *d*. (Shown in Fig. 2.) Through this opening *d*, and before the piece *c* is secured to the body of the bag, the loop of an elastic band *e* is passed, and is prevented from being withdrawn by a small cross-bar or 40 detainer *m*. (Shown in Fig. 3.) In the inclosing-flap is an opening *n*, through which that portion of the elastic band *e* is drawn when the inclosing-flap is secured in position.

In carrying out my invention an elastic 45 band is selected of the size desired, a loop of the elastic is then passed through the stiffening and holding piece *c*, and the cross-bar *m* is inserted in the loop projecting through the

opening in the piece *c*. The piece *c* is then secured to the bag by paste, gum, or any desired substance, the side of the piece *c* having the loop and cross-bar resting against the body of the bag. The outward-projecting portion of the elastic band is then passed through the opening *n* in the inclosing-flap *b*, 55 and this flap is then brought up and secured to the body of the bag in the usual manner.

In this condition the bag is ready for use and can be sold as an article of merchandise. When the bag is filled, the top portion is folded 60 over in the usual manner, and the elastic band is then brought up and over, as is readily understood. The bag is then securely closed and the contents prevented from escaping.

By the use of my improved attachment 65 binding strings or cords are dispensed with, the bags can be closed in much less time, and are always ready for immediate use.

Having thus described my invention, what I claim as new, and desire to secure by Letters Patent, is—

1. The combination, with the body of a bag, of a holding-piece attached to said body, an elastic binding-band attached to said holding-piece, and an inclosing-flap for securing the 75 holding-piece to the bag-body, said flap being secured to the body of the bag and provided with an opening through which the elastic band passes, as described, and for the purpose set forth.

2. The combination, with the body of a bag, of a holding-piece attached to said body and provided with an opening, an elastic binding-band, a cross-bar or detainer, and an inclosing-flap secured to the body of the bag and 85 provided with an opening through which the elastic band passes, all said parts being arranged and combined as and for the purpose set forth.

In testimony that I claim the foregoing I 90 have hereunto set my hand this 13th day of April, 1889.

JOHN S. FIELDER.
